CLAIM

The ornamental design for a souffle cup, as shown and described.

DESCRIPTION

FIG. 1 is a front perspective view

FIG. 2 is a front view

FIG. 3 is a back view

FIG. 4 is a left side view

FIG. 5 is a right side view

FIG. 6 is a top view; and,

FIG. 7 is a bottom view.

1 Claim, 7 Drawing Sheets(56)
